(57) **CLAIM**

We claim the ornamental design for a bottle, as shown and described.

DESCRIPTION

FIG. 1 is an isometric view of a bottle, showing the new design;

FIG. 2 is a top view of the bottle;

FIG. 3 is a rear-elevational view;

FIG. 4 is a left side-elevational view;

FIG. 5 is a front view;

FIG. 6 is a right side-elevational view;

FIG. 7 is a left side isometric view; and,

FIG. 8 is a bottom isometric view thereof.
